UNITED STATES PATENT OFFICE.

THOMAS C. EKLAND, OF WASHINGTON, PENNSYLVANIA.

DRAW SPIKE.

Application filed November 10, 1922. Serial No. 600,145.

To all whom it may concern:

Be it known that I, THOMAS C. EKLAND, a subject of the King of Sweden, and a resident of Washington, in the county of Washington and State of Pennsylvania, have invented certain new and useful Improvements in Draw Spikes; and I do hereby declare the following to be a full, clear, and exact description of the invention, such as will enable others skilled in the art to which it appertains to make and use the same.

The object of the invention is, to provide a simple, cheap and efficient device for lifting patterns in moulds, and the invention consists of certain novel features and details of construction, as will be more fully described hereinafter and finally pointed out in the claim.

I will now describe my invention, reference being had to the accompanying drawings, in which similar letters of reference indicate corresponding parts in the different figures, and in which,

Figure 1, is a side elevation of my improved pattern-lifting-screw. Fig. 2, is a similar view, partly in section, and Fig. 3, is a plan view of the adjustable plate thereof.

A, represents the screw proper, B, the adjustable plate, and C, the set-screw for securing the plate B, in a rigid position on the screw A.

The screw A, is provided on its lower end with a thread D, and on its upper end with an eye or handle E, which may be of any desired form.

The operation is as follows:

The screw A, is pushed down through the cope of the mould and screwed into the upper-half of the pattern; the adjustable plate B, is then pushed down on the screw, the underside of the plate resting on the top of the cope. The set-screw C, is then tightened and everything is in readiness for separating the pattern halves when the cope and drag are separated.

Heretofore, a simple device, called a spike, was used for this purpose and has proven to be inefficient, as often times the mould would pull off the end and drop, spoiling the job and causing the moulder to do his work over.

Having described my invention, what I claim and desire to secure by Letters Patent is:

A pattern-lifting-screw, consisting of the screw proper threaded on its lower end and a suitable handle formed on its upper end, an adjustable plate mounted on said screw and provided with a set-screw for securing said plate rigidly in position on said screw, all substantially as shown and for the purposes described.

In testimony that I claim the foregoing to be my own invention, I have hereunto set my hand in the presence of two subscribing witnesses.

THOMAS C. EKLAND.
